Jules Falkenburg

UNITED STATES PATENT OFFICE

JULIUS FALKENBURG, OF NEUWIED-ON-THE-RHINE, GERMANY

ROWING APPARATUS FOR GYMNASTIC EXERCISES

Application filed June 25, 1927, Serial No. 201,497, and in Germany May 25, 1927.

Gymnastic exercises are nowadays practiced generally on account of their useful effects. The healthy result of the rowing sport is generally known. It has already been proposed 5 to execute rowing-exercises not only on the water but also at home. The apparatus designed for this purpose are however very complicated and much too expensive to be generally adopted.

10 This invention relates to a rowing-apparatus for gymnastic exercises and which comprises a disk-arrangement controlled by a spring and exerting a strong friction-effect, in combination with a pressure-spring, and 15 with the insertion of a ratchet wheel with counter wheel, the oars being directly or indirectly attached to said counter wheel.

An embodiment of the invention is illustrated, by way of example, in the accompanying drawings in which:—

Fig. 1 shows the rowing-apparatus in side elevation.

Fig. 2 is a vertical section of Fig. 1.

Fig. 3 is a top plan view of Fig. 1.

25 Fig. 4 shows the apparatus in side elevation in the position of use.

Fig. 5 is a top plan view of Fig. 4.

The apparatus consists essentially of two conical friction-disks *a* and *b*, two circular 30 rows of teeth *c* and *d* engaging the one with the other, of a spring *e* and of a screw-spindle *g*. The lower friction-disk is conical and of solid cross section, the upper friction-disk *b* being hollow and having a conical bore, cor-

35 responding with the circumference of the friction-disk *a*. Owing to the conical shape of the friction disks *a* and *b* a strong friction is produced when disk *b* is being rotated on disk *a*. A tubular extension *f* on the top end 40 of disk *b* has a thickening in which teeth *c* are cut. A guide ring *j* mounted on the tubular extension *f* above the teeth *c* has teeth *d* in its lower end, engaging with the teeth *c*. A spring *e* exerts a permanent pressure upon

45 ring *j* so that the teeth *d* are normally in engagement with the teeth *c*. A fork *h*, partly embracing said ring *j*, is hingedly fixed on the same. In the end *k* of each fork *h*, two 50 of said devices belonging to one rowing-apparatus, an oar *i* is attached. The tubular

upwardly directed extension *f* of the hollow-disk *b* projects from the ring *j* so that this ring is securely guided when its teeth *d* are disengaged from the teeth *c* of disk *b* so that said ring is shifted in upward direction. The ring *j* is rotated so that its teeth disengage from the teeth *c* of the disk *b* each time when the oar is being pushed. Above the end of the tubular extension *f* of the hollow disk *b* two disks *l* are mounted, balls being inserted between the same.

Instead of the disks a simple sliding ring may be used. The ball-bearing is designed on the one hand to prevent friction of the guide-ring *j* and on the other hand to prevent a nut *m* getting loose when the apparatus is being used. Although the spring *e* and the ball bearing are very practical, they are not absolutely necessary for the apparatus.

Two devices as described are mounted the one at the right and the other at the left, each on a bracket *n* of a frame *o* and by means of a counter-nut *p* screwed onto the lower end of the screw-spindle *g*. Accidental rotation of each device is prevented by a pin *q*, projecting from the lower end of the solid disk *a* and engaging with the corresponding bracket *n*. In the frame *o* a roller-seat *r* is arranged and a foot-rest *s* is fixed.

The operation of the apparatus is as follows:—

The nut *m* is tightened to clamp the disks *a* and *b* the one on the other in accordance with the energy to be exerted at the rowing.

The oars *i* are pushed forward, and at this movement the rings *j* are rotated so that the teeth *d* disengage from the corresponding teeth *c* to drop into engagement automatically under pressure of the spring *e*. The oars are then pulled, this requiring considerable energy, depending on the tightening of nut *m*. At this pulling of the oars the hollow disk *b* is rotated on the solid disk *a*, the guide-ring rotating however at the pushing and pulling of the oars. The space between the disk *l* and the washer of nut *m* might be filled with a spacer *t*.

I claim:—

1. A rowing apparatus for gymnastic exercises, comprising a friction-resistance

brake, said brake characterized by two interfitting friction cones, the outer of said cones having an enlarged tubular extension, and teeth formed on said enlarged extension.

5 2. A rowing apparatus for gymnastic exercises, comprising a friction-resistance brake, said brake characterized by two interfitting friction cones the outer of said cones having an enlarged tubular extension, teeth formed on said enlarged extension, a ring having teeth in its lower edge slidably mounted on said tubular extension above said enlarged portion, and a ball bearing on the top end of said tubular extension.

10 15 In testimony whereof I affix my signature.
JULIUS FALKENBURG.
